UNITED STATES PATENT OFFICE

HERMAN C. GEBAUER, OF ST. PAUL, MINNESOTA, ASSIGNOR OF ONE-HALF TO BERNARD J. MALMGREN, OF ST. PAUL, MINNESOTA

ILLUMINATED STREET SIGN

Application filed February 27, 1929. Serial No. 343,008.

This invention relates to means for efficiently displaying the names of streets, highways and the like, particularly at street intersections.

5 It is my object to provide an improved sign of this class adapted for attachment to street lamp-posts. More particularly, it is my object to provide improved means for mounting a plurality of signs or name plates 10 in position for illumination by artificial light as well as by daylight and to generally improve the construction and arrangement for properly illuminating such signs or plates and for protecting them from moisture.

15 This invention also includes a novel arrangement adapted to facilitate the mounting of the signs on posts and the replacement of the breakable parts when they become broken.

20 The invention will be best understood by reference to the accompanying drawings in which Figure 1 is a plan view of one form of my improved device; Fig. 2 is a fragmentary section on an enlarged scale and taken on the line 2-2 of Fig. 1; Fig. 3 is a side elevation of the device showing its relation to a street lamp of common type; Fig. 4 is a perspective view of one of the auxiliary 25 reflectors; Fig. 5 is a side elevation showing an alternate form of my device mounted upon a street lamp of the cluster type and Fig. 6 is an enlarged fragmentary section taken on the line 6-6 of Fig. 5.

30 I provide a series of arcuate clamping members 7 adapted to engage the upright post 8 (Fig. 3). Each of the members 7 has a pair of integral arms 9 projecting radially outward from its ends and these arms have outer extremities 10 which are bent to project in parallel relation to each other. A series of bolts 11 secure adjacent arms 9 together near their outer ends and a second series of bolts 12 near the inner ends of the arms 9 are provided to contract the several members 7 into clamping engagement with the post 8. Where the device is used at the common intersection of two streets, four of the members 7 are provided as clearly shown in Fig. 1 and a street sign

or name plate 13 is secured to each pair of the arms 9.

In the form of my invention shown in Figs. 1 to 4, inclusive, I mount each of the street signs or name plates 13 in substantially horizontal position and support it in a frame consisting of end pieces 14 connected by longitudinal bars 15 and 16 and an oblique support 17 for a reflector 18. Between horizontally extending flanges 55 on the ends 14 and channels 15 and 16 are mounted a translucent plate 19 covering the sign 13 above and a second translucent plate 20 beneath the sign 13. These plates 19 and 20 and bars 15 and 16 completely enclose 60 the sign 13 and protect it from the weather or moisture. The front or outer bar 16 is provided at its ends with a pair of ears 21 which are slotted as indicated at 22 to receive bolts 23 for attaching said member to 65 the end pieces 14 of the frame. The bolts 23 may be loosened to permit withdrawal of the horizontal flanges from engagement with the plates 19 and 20. When withdrawn 70 from engagement with said plates, the bar 75 16 may be lowered to the position shown in dotted lines in Fig. 2 and thus allow access to the sign 13 when the same is to be inserted or replaced or for the replacement of the translucent plates 19 and 20, which 80 may be broken in use.

Projecting above and along the bar 16, and preferably secured thereto, is an auxiliary reflector 24 adapted to reflect light from a centrally located source 25 through the 85 sign 13, as indicated in Fig. 3. The main reflector 18 projects obliquely outward and downward beneath the sign 13 to reflect the image of the sign 13 and make it visible to observers on the street in well known manner. Near the junction of the auxiliary reflector 24 and channel member 16, openings 90 26 are formed in said reflector to allow the escape of moisture and obstructing matter, such as leaves, snow and the like, which 95 might otherwise collect on the plate 19. The end pieces 14 of the frame are secured by bolts 27 to the arm ends 10, the pair of the bolts 27 supporting each sign being arranged in axial alignment with each other to permit 100

tilting of the frames, as indicated in dotted lines in Fig. 3. Such tilting is sometimes desirable to compensate for the height of a particular source 25 of light.

In the use of the form of my device described above, it will be evident that during the daytime the images of the horizontal signs 13 are cast upon the reflectors 18 where such images are visible from the several sides of the post 8. At night, light from the lamp or source 25 passes through the translucent plates 19 and 20 and casts the image of the sign 13 upon the reflector 18. Where a single source of light is provided, as in Fig. 3, it will be evident that the direct rays from such source are directed obliquely outward and in the absence of my auxiliary reflectors 24 the signs 13 are not properly illuminated at their outer edges. Thus the reflected rays from the auxiliary reflectors 24 illuminate the otherwise unilluminated outer edges of the signs so that the images are properly illuminated and cast upon the main reflectors 18.

In the alternate form of my invention, shown in Figs. 5 and 6, I provide an arrangement which is particularly advantageous with a street lamp-post 28 of the cluster type having a lamp 29 for each of the several street signs. In this alternate form the arcuate clamping members 7 and radial arms 9 with parallel ends 10 are like those of the preferred construction, but the frame, reflectors and signs are differently arranged. The signs proper 30, of the alternate form, are disposed in substantially vertical position between protecting glass plates 31 and a reflector 32 is disposed obliquely behind the sign 30 instead of beneath the sign as in the preferred construction. Each of the signs 30 is supported in a frame consisting of a pair of parallel end members 33 connected by a reflector support 34 and rigid longitudinal angle bars 35. The sign 30 and plates 31 are secured together between the longitudinal angle bars 35 by a second pair of angle bars 36 and bolts 37. To protect the sign 30 and make a moisture tight joint around the edges of the plates 31, packing 38 of channel shape is extended entirely around the plates 31 and sign 30. This packing 38 is preferably made of suitable soft rubber which is firmly gripped in sealing relation with the plates 31 by the action of the bolts 37. Obviously, such packing may be applied to the preferred construction illustrated in Figs. 1 to 4, inclusive, if desired. The reflector 32 is preferably constructed from a non-corroding metal plate which may be quickly and easily inserted, as indicated in dotted lines in Fig. 6. A flange 39 is formed on the support 34 along its lower edge to retain the lower edge of the reflector 32 and another flange 40 along the upper edge of the support 34 is arranged

to retain the upper edge of the reflector. These flanges 39 and 40 are sufficiently widely spaced to permit sliding the reflector 32 up to dotted line position shown in Fig. 6 where its lower edge is free to pass outward past the flange 39. It will be noted that an opening 41 of substantial size is formed between the flange 39 and angle member 35 at the bottom of the frame. This opening allows the escape of moisture, snow and other obstructing material from the space between the plates 31 and reflector. The ends 33 of the sign supporting frames are secured by bolts 42 to the ends 10 of the arms 9 as in the preferred embodiment of my invention.

It will now be understood that in the alternate form, shown in Figs. 5 and 6, one of the lamps 29 is located above each of the reflectors 32 and the tops of the frames are open so that the reflectors 32 are illuminated by daylight or when the lamps 29 are illuminated, the rays received by the reflectors 32 are directed substantially horizontally through the translucent plates 31 and signs 30. Thus the signs are illuminated and readable at all times.

To mount a sign of either type above described upon the post 8 or 28, the assembly consisting of three of the signs connected together by the bolts 11 and 12 may be passed into engagement with the post without removing the lamp and then the fourth unit consisting of an arcuate member 7 with arms 9 and sign attached may be quickly and easily secured to the other three units by the use of additional pairs of the bolts 11 and 12. Bands of steel of the desired rigidity and strength are employed in the construction of the members 7 and arms 9 and such members and arms are somewhat resilient to permit clamping in secure engagement with the supporting posts. Considerable range of adjustment and secure clamping is insured by my arrangement of the arms 9, having their ends separable to varying degrees, as indicated in Fig. 1.

I prefer to utilize inexpensive stencils for the signs 13 and 30 so that the signs may be replaced with a minimum of expense when, as frequently occurs, they become broken. It will be evident that the signs proper or stencils are efficiently protected from the weather and therefore may be constructed from paper or paper board of more or less destructible nature.

Having described my invention what I claim is new and desire to protect by Letters Patent is:

1. A street sign comprising a plurality of similar units, each unit having a clamping member adapted to engage an upright post or the like, each of said members being formed at its ends with a pair of outwardly projecting arms arranged to be secured to the arms of the adjacent unit, the outer ends

of the arms of each unit being disposed in parallel relation to each other, a frame secured between each pair of parallel ends and a sign on each frame.

5 2. A street sign comprising at least three similar units, each unit having a clamping member adapted to engage an upright post or the like, each of said members being formed at its ends with outwardly projecting arms arranged to be secured to the arms of the adjacent unit in pairs, and the arms of each pair converging outward, means for securing the inner ends of said arms of each pair in spaced relation to each other, a frame 10 secured to each pair of arms and a sign on each frame.

15 3. In a street sign adapted to be secured to a lamp-post or the like, a substantially horizontal and translucent sign adapted to be illuminated from above, a reflector disposed at an acute angle with said sign beneath the same to display the image of said sign and an auxiliary reflector projecting above said sign to reflect light therethrough.

20 4. In a sign of the class described, the combination with a central source of light and a series of substantially horizontal, translucent signs disposed around said source, a series of reflectors extending 25 obliquely downward and outward from said source beneath said signs to receive the images of the same and a series of auxiliary reflectors projecting above said signs adjacent to their outer edges to reflect light through said signs.

In testimony whereof, I have hereunto signed my name to this specification.

HERMAN C. GEBAUER.
